UNITED STATES PATENT OFFICE.

JOSEPH J. BLACK, OF DAYTON, OHIO, ASSIGNOR TO THE MASTER TIRE & RUBBER COMPANY, OF DAYTON, OHIO, A CORPORATION OF OHIO.

DESIGN FOR A TIRE.

Application filed April 13, 1923. Serial No. 5,815. Term of patent 3½ years.

To all whom it may concern:

Be it known that I, JOSEPH J. BLACK, a citizen of the United States, residing at Dayton, in the county of Montgomery and State of Ohio, have invented a new and ornamental Design for a Tire, of which the following is a specification, reference being had to the accompanying drawing, forming part thereof.

In the drawing, Fig. 1 is a plan view of the tread of my tire; and Fig. 2 is a section on the line 2—2 of Fig. 1.

I claim:—

The ornamental design for a tire, as shown.

JOSEPH J. BLACK.
